DESIGN FOR AN AERATOR OR THE LIKE

David Chapman, Chicago, Ill., assignor to
Knapp-Monarch Company, St. Louis, Mo., a
corporation of Missouri

Application December 11, 1940, Serial No. 97,245

Term of patent 7 years

To all whom it may concern:

Be it known that I, David Chapman, a citizen
of the United States and a resident of Chicago,
in the county of Cook and State of Illinois, have
invented a new, original, and ornamental Design
for an Aerator or the like, of which the following
is a specification, reference being had to the ac-
companying drawing, forming a part thereof.

Figure 1 is a top plan view of an aerator, show-
ing my new design;

Figure 2 is a side elevational view thereof;

Figure 3 is a front elevational view of the upper
portion of the aerator, and

Figure 4 is a rear elevational view of the upper
portion thereof. The portions of Figures 3 and 4
below the broken line at the bottom are the same
as the lower portion of Figure 2.

I claim:

The ornamental design for a aerator or the
like, substantially as shown and described.

DAVID CHAPMAN.
